FRICITION CONNECTION FOR SPINDLES AND BOBBINS OR SPOOLS.

Application filed November 1, 1922. Serial No. 598,412.

This invention relates to friction connections between spools or bobbins used in textile manufactures and the spindles, holders, pins or mountings upon which the spools or bobbins are carried, or held against rotation, or by which they are driven.

Both when winding and unwinding strands or filaments, such as yarns, thread, cordage, or wires, or at any stage or several 10 of the stages in the process of manufacture or handling of such filaments, it is desirable to provide for the certain connection of the bobbin or spool to the spindle and its attachments, so that the connection shall 15 operate to fix against relative rotation the bobbin or spool and the spindle, except when the forces tending to rotate one in respect to the other reach or exceed a certain predetermined minimum value.

20 It is also desirable in all stages of manufacture of wound packages, such as the spools, bobbins, cheeses, or cops formed during the manufacture of all classes of textiles, to provide, when it is necessary to provide 25 for rotating a bobbin or spool in respect to a spindle and its appurtenances, for a regulated, controllable, and dependable drag between the members of the unit comprised of a spool or bobbin and its spindle.

30 For example, in certain winding operations incidental to doubling, to drawing, to roving, or when winding only, spools receiving the sliver, roving yarn, or doublet are mounted on stationary spindles so as to be 35 turned by the drag of the strand delivered by a power-driven revolving flyer. In other instances a spool or bobbin is mounted upon a power-driven rotating spindle and the strands are delivered by a guide which may 40 or may not revolve about the spool.

In either case, rotation of the spool relative to its spindle or support must correspond to the rate of delivery of the strand independently of the rate of rotation of the 45 spindle or of the delivery instrument, such as the flyer, and this rotation is induced by increase in tension on the winding strand. The turning moment on the spool is measured by this tension and the radius of the 50 wound mass. The turning moment necessary to rotate the spool or bobbin in relation to its support, under ideal conditions, should be contrived to remain constant during variation of the wound diameter of the package, spool or bobbin, and during variation

of the thrust of the spool or bobbin against its support induced by changed weights of the wound mass. It should never approach or exceed the breaking strain on the strand.

The spools or bobbins referred to for various uses vary in size, from large spools or bobbins intended to hold a substantial weight of heavy cordage, wire or woolen yarn to the light and delicate spools or bobbins, chiefly employed in the manufacture of silk 65 and cotton.

I am aware that frictional resistance has heretofore been provided, especially in the case of spools supported on vertical spindles 70 to receive heavy weights of yarn, by inserting, between a flange on the spindle and the spool or bobbin, a washer of leather, felt or similar friction material upon which the lower end of the bobbin or spindle rests. If the diameter of such a washer be properly chosen, and the spools have perfect 75 heads, substantially the desired frictional resistance may be obtained during a part of the winding operation, but as the weight of the spool or bobbin increases, it is necessary 80 to lift it from the spindle and substitute a washer of another size, several such changes being a frequent incident to proper winding of large spools, especially of relatively weak yarns or rovings.

I am also aware of sundry friction devices 85 adapted to connect bobbins and spindles, but so far as I am aware these devices all suffer either from the defect of not providing sufficient drag, thus causing the minimum tensioning at which the bobbin or spool will 90 slip on the spindle to be too low; or, on the contrary, from being so efficient as for all practical purposes to lock the spindle and the bobbin together, so that forces approaching the breaking strains or exceeding them 95 will be required to rotate the bobbin or spool in respect to the spindle by forces transmitted along the strand. Winding by machines as now practiced suffers serious losses due 100 to failure of the art to provide so far as I am aware, an efficient friction device which will cooperate with spool or bobbin to grip it at normal tensions and release it when necessary.

A principal object of the present invention is therefore to preclude the difficulties alluded to by the provision of means adapted to the several situations mentioned, and constituting an improved kind of frictional connec- 110

tion between a spindle or its attachments and a bobbin or spool mounted upon a spindle; to provide for increasing the frictional resistance to relative turning of bobbin or spool and spindle in accordance with the longitudinal thrust exerted by the spool or bobbin, for example, due to the weight of the yarn wound upon it, and independently of minor defects of the spool or bobbin head; and to provide means for connecting a spindle and its appurtenances to the bobbin or spool, which will cause one of these members certainly to move with the other, but which will yield upon the exertion of a predetermined minimum resistance to motion of one in respect to the other; and which will enable a bobbin or spool which has so yielded after the exertion of the said minimum stress, to again become relatively fixed when the stress is relieved, or to continue to slip under a relatively constant resistance to such slippage.

The invention includes for the above purposes a resilient tractor pad or member provided with engaging or tractor devices adapted and arranged to provide the desired kind of engagement or bearing between the spindle and the bobbin or spool, and for this purpose adapted to attach itself to the spindle, (or to the bobbin or spool) and frictionally to bear upon the bobbin and spool (or the spindle). This characteristic device of the invention may be used with or without the felt washer of the prior art, and is adapted for use without change, except of dimension, in the various situations mentioned and others which will be apparent.

Certain preferred ways only of accomplishing the purposes of my invention are illustrated in the drawings, in which:

Fig. 1 is a side elevation partly broken away showing a winding spindle and a spool mounted thereon in use with a frictional device between spindle and spool corresponding to the invention;

Fig. 2 is a fragmentary side elevation, partly in vertical cross section and to larger scale than Fig. 1, showing the position of the parts when the spool is empty;

Fig. 3 is a view similar to Fig. 2 but showing the parts in the position which they occupy when the spool is substantially filled;

Fig. 4 is a plan view of a cushioning and tension regulating device forming an essential feature of the present invention;

Fig. 5 is a plan view similar to Fig. 4 but showing a modified arrangement of parts;

Fig. 6 is a vertical cross section to greatly enlarged scale on a line such as 6-6 of Fig. 4;

Fig. 7 is an edge elevation of a device such as shown in Fig. 5 but illustrating a further modification.

Fig. 8 is a section of the device in use to connect a spool to a driven spindle, such as

the tubular spindle of a spool winding machine;

Fig. 9 is a plan view of one of the friction elements of a size suitable to connect a bobbin and a spindle of a spinning frame; and

Fig. 10 is a diagram section showing the effect of one of the friction elements.

Referring to Figs. 1, 2, 4 and 8 of the drawings, Figs. 1 and 2 show a vertical spindle 1, which may be either a rotary or a stationary spindle, and in either case carries a flange 2 fastened to it, as by set screw 4, and serving as a stop or rest for the spool 5 having heads 6 and 7. In Fig. 8, which shows a common form of spooler having a spindle 1^a, a tubular spindle 1^b, and a whorl 20 having a flange 21 fast to the tubular spindle 1^b, the flange 21 serves the same purpose as a stop or rest for the spool, which may be of any usual kind having, for example wooden heads 25 armored with brass sheaths 26 spun into grooves in the heads.

In either case, the spool (or a spinning bobbin on a spinning spindle, which may be equipped with the present new devices with great benefits in operation as will be apparent to textile artisans) is related to and caused to be frictionally coupled to the spindle by interposing between the flange against which one end of it abuts and the abutting head of the spindle or bobbin, a friction device adapted to adhere strongly to either the bobbin or spool on the one hand, or to the flange on the spindle, or the spindle, or both, on the other hand, and to bear against that member of these abutting parts to which it does not adhere with a frictional resistance dependent in the first instance upon the force of compression to which it is subjected.

In the instances shown, the friction device sticks more firmly to the flange and spindle than to the bobbin or spool, and preferably comprises a substantially flat resilient ring or annular disk 9 of rubber vulcanized to a highly resilient soft state, or other suitable resilient material which rests upon the upper surface of the flange 2, concentrically with the spindle 1. This disk is provided with a central bore 5 for the spindle, and with plurality of spaced openings, preferably arranged symmetrically with respect to the center of the disk, and in each of these openings a vertically movable plug 10 is arranged (Fig. 6). The plugs are of slightly less diameter than the respective openings and are thus isolated from the body portion of the disk by annular recesses 11. These plugs are preferably of the same material as the body of the disk and each integrally united therewith by a relatively thin bridge member 12 of sufficient tensile resilience to permit the plugs to move downwardly by tensile stretch of bridges 12

with relative ease into their respective openings when subjected to pressure. In the normal position, each plug projects a substantial distance above the upper surface of the disk, so that a chamber or recess 13 is provided beneath the plug. Thus when the upper surface 14 of the plug is subjected to pressure the plug is free to move bodily down against the tension of the bridge member 12.

When this invention is to be used in winding large spools, as for heavy woolen yarns, it is preferred to place, underlying the lower surface of the head 7 of the spool, the usual friction washer 15 preferably formed of relatively flexible material such as felt, or the like, and in the normal position of the parts this washer rests upon the upper surface of the disk 9 and contacts with the upper ends of the projections or plugs 10. The plugs underlying the felt washer produce regions of compression 16 in the felt washer, the upper surfaces of these regions being areas of frictional contact relied upon to oppose turning of the spool. These regions of pressure are indicated by the darker shading at these regions, which as shown in Fig. 2, are of a diameter corresponding to the effective area of the tips of the corresponding plugs in contact with the felt when the weight supported and pressure on the felt and plugs is at a minimum. These regions of compression 16 of the felt washer 15 thus define areas of effective pressure contact between the washer and the lower face of the head 7 of the spool, the frictional effect of these areas of pressure contact being at a minimum when the weight of the spool is least. During the winding operation, as the weight of the spool is increased by the growing yarn mass, the pressure upon the plugs 10 is constantly augmented so that the regions 16 increase in size and the plugs gradually move downward against the tension of the bridge members 12 until the upper surfaces of the plugs may lie substantially flush with the upper surfaces of the disk. During such movement the regions 16 gradually increase in area, and the pressures upon them are augmented so that their braking effect on the lower face of the spool continually increases, the position of the parts when the spool is weighted being indicated in Fig. 3. It will thus be evident that as the thread mass on the spool increases in diameter and the lever arm with which the strand acts upon the spool to turn the latter increases, the frictional resistance to turning will likewise gradually increase.

The friction regulating device herein shown has the additional desirable function of serving as a cushion for the heavy spool so that even though the operator carelessly drops the spool upon the spindle no damage to the spool or other parts will be occasioned.

The use of the felt 16 is optional, and in many situations is not recommended.

Referring again to Figs. 1 and 8, and to the diagram, Fig. 10, the upwardly projecting plugs 10 yieldingly suspended on the integral resilient bridges 12 are particularly effective instruments for the purposes above explained. Being freely and lightly resilient in the direction of the axis of the spindle, these plugs yield readily to roughnesses and projections on the face of the spool or bobbin; and whether or not a washer such as 15 is interposed, they give the connection between the spindle and bobbin the property of resiliently yielding through a short relative turning motion before slippage between the spool or bobbin head and the friction device takes place. As shown in Fig. 10, for example, if we assume the head 25 of the spool 5^a to be relatively stressed in the direction of the arrow, the plug 10 will move with the head 25 to the left from the dotted to the full-line position, against the resilient resistance of the bridge 12, which is stretched upward on the near side and downward on the far side of every plug 10 tipped over by the stress on head 25. When the plug can move no further, the head 25 will slip, but the bridges 12 are still effective to keep the plugs 10 in contact with the surface of 25, whether this runs true or not. Heavy weights are not essential to this action, which is competently effected by the friction devices 9, 10 for such relatively light masses as empty spinning-bobbins and small spools, such as are used for winding cotton thread.

Whatever the kind of spool or bobbin, the plugs 10 are highly sensitive to increases of weight, and the tension required to cause slippage varies with the thrust, and increases about in proportion to the growth of diameter of the winding when the resilience of the material of the tension disk and the size and number of the plugs 10 are properly chosen, as will be apparent.

The disks 9, 9^a or 9^b may adhere to the flanges of the spindle, pin or whorl on which they rest by mere surface friction; or, as shown in Fig. 8, the central hole b may be a grasping fit on the spindle. If desired the disks 9 may be inverted to adhere to the bobbin or spool, and have the plugs 9 bear on the machined metal flange, but this is not recommended in view of the superior effect of the plugs 9 as frictional contactors with the very variable surfaces of bobbins and spools.

In Fig. 5 a modified arrangement of tension regulating disc 9^a is shown as provided with a plurality of series of the resiliently supported plugs, indicated at 10^a and 10^b respectively. With such an arrangement the friction washer may be so small as to engage only the inner series of plugs, or may be

made of a diameter to contact with the plugs of both series, as desired, thus giving a greater range of tension and permitting the same regulating device to be used with spools of widely different sizes.

In Fig. 7 a further modification is indicated in which the regulating disk 9' is provided with a plurality of series of plugs 10^e, 10^e and 10^f of which the plugs of the inner series 10^e are somewhat higher than those of the intermediate series 10^e, which in turn are higher than those of the outer series. With this arrangement the increase in frictional resistance to turning may be very delicately varied as the plugs of the two outer series do not become active until the plugs of the inner series have been partly compressed. Thus the frictional contact surface may vary through very wide limits, providing an accurate adjustment of the retarding action.

As will be clear from inspection of Fig. 6, the support of the plugs 10 by means of the relatively thin bridge member 12 permits such plugs to be depressed much more readily than the main body of the disc 9, thus giving a far greater resiliency to the device than would be the case were these plugs formed as mere projections upstanding from the surface of the resilient disc. While such elastically supported plugs or projections are thus preferable for providing great delicacy in action, it is to be understood that projections otherwise supported might well furnish some at least of the advantages of the present device, and it is contemplated that in its broader aspects the present invention may be embodied in other and equivalent arrangements differing in detail from those herein disclosed.

Mention above of "bobbins" and "spools," with which the device is indifferently useful, is meant to be inclusive of either, and in the claims either word is to be understood as generically applying to any species of container or support for a wound mass.

What I claim is:

1. A friction device comprising a perforate tension disk adapted to be interposed between surfaces of a spindle and of a bobbin or spool respectively for the purpose of acting as a brake against relative rotation between said surfaces, and having one or more resiliently supported plugs adapted to engage with one of said surfaces and to be displaced against its resilient support by pressure in the direction of the axis of the spindle.

2. A friction device comprising a resilient perforate tension disk adapted to be interposed between surfaces of a spindle and of a bobbin or spool respectively for the purpose of acting as a brake against relative rotation between said surfaces, and having one or more resiliently supported integral plugs adapted to engage with one of said surfaces

and to be displaced against its resilient support by pressure in the direction of the axis of the spindle.

3. A friction device for use as a brake against relative motion between a spindle 70 and a spool comprising a perforate resilient rubber disk adapted to lie between a surface of the spindle and a surface of the spool, and having a plurality of integral plugs supported by integral bridges and normally held thereby to project from one face of said disk.

4. The combination with a substantially vertical spindle and a spool thereon, of a support for the lower head of the spool comprising 80 a disk concentric with the spindle, said disk having a plurality of spaced projections upstanding from its surface, and means for yieldingly permitting lateral motion of the projections in respect to the disk.

5. The combination with a spindle and a spool mounted thereon, of means for retarding rotation of the spool comprising a disk concentric with the spindle, a plurality of 90 spaced elements projecting from the face of said disk toward the adjacent head of the spool, and resilient tension means for holding said elements in normal relation to the disk.

6. The combination with a spindle and a spool mounted thereon, of means for retarding rotation of the spool comprising a disk concentric with the spindle, said disk having an opening therein, a plug within the 100 opening, one end of the plug normally projecting beyond the plane of the disk and toward the adjacent head of the spool, and resilient means connecting the plug to the disk.

7. The combination with a vertical spindle and a spool thereon, of means for supporting and cushioning the spool comprising a rubber disk surrounding the spindle and below the lower head of the spool, and having a series of friction plugs projecting upwardly from the disk toward the lower head of the spool, said plugs being more readily depressed than the body of the disk.

8. The combination with a vertical spindle and a spool mounted thereon, of supporting means for the lower head of the spool, said supporting means providing resiliently supported frictional engaging surfaces contacting with the lower head of the spool and constructed and arranged automatically to increase in braking effect as winding of material upon the spool progresses.

9. The combination with a vertical spindle having a radial flange and a spool upon 125 the spindle, of cushioning and retarding means for the spool comprising an annular rubber disk concentric with the spindle and below the lower head of the spool, said disk having a plurality of openings therein, rub-

ber plugs within said openings, said plugs normally projecting upwardly from the upper face of the disk, resilient suspension means connecting the plugs to the body of the disk to permit resilient lateral displacement and depression of the plugs under pressure.

10. The combination with a spindle and a spool thereon, of friction means for retarding relative rotation of the spindle and the spool comprising an annular rubber disk concentric with the spindle and having an integral plug partially separated therefrom and projecting from the surface thereof in 15 the direction of and adapted to contact with the adjacent end of the spool, the integral connecting bridge between the substance of the disk proper and the plug having tensile resilience and being adapted to be stretched 20 by pressure of the spool head against the outer end of the plug.

11. The combination with a spindle and a spool thereon, of friction means for retarding rotation of the spool comprising an interposed disk having a projecting integral 25 plug supported for resilient deformation into alignment with the surface of the disk under pressure of the spool head, such deformation occasioning the tensile stretching of the integral junction between the plug and 30 the body of the disk.

12. The combination with a spindle and a spool thereon, of means for opposing free rotation of the spool comprising a disk concentric with the spindle and having resiliently supported elements projecting from its surface toward the adjacent head of the spool, one of said elements projecting to a greater distance than another.

Signed by me at Boston, Massachusetts, 40
